UNITED STATES PATENT OFFICE

104,179

DESIGN FOR A JUG

Sol K. Berk, Brookline, Mass.

Application August 13, 1936, Serial No. 64,388

Term of patent 3½ years

To all whom it may concern:

Be it known that I, Sol K. Berk, a citizen of the United States and residing at Brookline, in the county of Norfolk and State of Massachusetts, have invented a new, original, and ornamental Design for a Jug, of which the following is a specification, reference being had to the accompanying drawing, forming a part thereof.

In the drawing:

Fig. 1 is a top plan view of a jug showing my new design.

Fig. 2 is a side elevational view thereof.

Fig. 3 is a side elevational view taken from the side opposite that shown in Fig. 2.

I claim:

The ornamental design for a jug substantially as shown.

SOL K. BERK.
